[57] CLAIM

The ornamental design for a casing for a power lock, as
shown and described.

DESCRIPTION

FIG. 1 is a perspective view from above and to the rear
of one end and the interior of a casing for a power lock
showing my new design;

FIG. 2 is an end elevational view thereof;

FIG. 3 is a plan view of the casing taken from a position
opposite to that shown in FIG. 4;

FIG. 4 is a plan view of the casing interior; and

FIG. 5 is a perspective view (a) of the casing bottom
taken from a position opposite to that shown in FIG. 1,
and (b) of the end of the casing opposite to that shown
in FIG. 1.
